US0D1004105S

(12) **United States Design Patent** (10) **Patent No.:** **US D1,004,105 S**
(45) **Date of Patent:** **** Nov. 7, 2023**

(54) **FLOW SENSOR**

(71) Applicant: **RHAEOS, INC.**, Evanston, IL (US)

(72) Inventors: **Adam M. Zysk**, Chicago, IL (US);
John Charles Skelton, Minneapolis,
MN (US); **Michael Alan Fry**,
Stillwater, MN (US); **Adam L.**
Gullickson, Stillwater, MN (US)

(73) Assignee: **RHAEOS, INC.**, Evanston, IL (US)

(***) Term: **15 Years**

(21) Appl. No.: **29/815,241**

(22) Filed: **Nov. 12, 2021**

(57) **CLAIM**

The ornamental design for a flow sensor, as shown and described.

DESCRIPTION

FIG. 1 is a top, front, left perspective view of a flow sensor, showing our new design;

FIG. 2 is a top, front, right perspective view thereof;

FIG. 3 is a left side elevation view thereof;

FIG. 4 is a right side elevation view thereof;

FIG. 5 is a front elevation view thereof;

FIG. 6 is a rear elevation view thereof;

FIG. 7 is a top plan view thereof; and,

FIG. 8 is a bottom plan view thereof.

The broken lines of even length shown in the drawings illustrate portions of the flow sensor that form no part of the claimed design.

1 Claim, 8 Drawing Sheets
